UNITED STATES PATENT OFFICE.

ALBERT J. SLAUGHTER, OF WASHINGTON, VIRGINIA.

BOTTLE-STOPPER.

1,029,473.

Specification of Letters Patent. Patented June 11, 1912.

Application filed April 8, 1911. Serial No. 619,744.

To all whom it may concern:

Be it known that I, ALBERT J. SLAUGHTER, a citizen of the United States, residing at Washington, in the county of Rappahannock and State of Virginia, have invented 5 new and useful Improvements in Bottle-Stoppers, of which the following is a specification.

This invention relates to bottle stoppers, 10 and has for an object to provide an improved stopper of this character which can be applied to the bottle without resorting to the use of permanent fastenings and constructing the said stopper obviating the 15 necessity of removing it from the bottle by means of extracting implements.

A still further object of the invention is 20 to employ a spring fastening device engaging a substantially ratchet surface at the neck end of the bottle so that the stopper can be effectively clamped to the bottle to form a perfect air tight connection.

In the drawing, forming a portion of this 25 specification and in which like numerals of reference indicate similar parts in the several views:—Figure 1 is a side elevation of a portion of a bottle showing my improved stopper applied thereto. Fig. 2 is a section taken on the line 2—2 of Fig. 1. Fig. 3 30 is a section taken on the line 3—3 of Fig. 2. Fig. 4 is a section taken on the line 4—4 of Fig. 1.

The bottle neck 1 is provided with a flanged upper end 2 which is formed at 35 diametrically opposite sides to provide oppositely inclined surfaces. Each surface is corrugated on its underside, as shown at 3 in Fig. 1 of the drawing. The flange 2 is provided with diametrically disposed recesses 4 for a purpose to be hereinafter described.

The cap may be of metal or any other material which may be found most desirable for the purpose intended. As illustrated, the cap is provided with a depending peripheral flange 6 which extends downwardly over the flanged end 2 of the neck. At the center the cap 5 is provided with a pivot stud 7 which extends through 50 the body portion 8 of a clamp 9. This clamp is formed preferably from a single length of sheet metal or wire, and as illustrated, it is bent to form bowed spring-forming portions 10 which extend downwardly 55 over the sides of the flanged end 2 of the bottle and then under the flange to form

locking elements 11 which are of concavo-convex form in transverse section, as shown in Fig. 3 of the drawing, for locking engagement with the correspondingly corrugated surfaces 3 hereinbefore described. 60 From the portions 3 the ends of the clamp extend downwardly against the sides of the neck, as shown at 12, and then outwardly from the neck, as shown at 13. Each extremity is then bent on itself, as shown, and the end 14 is extended upwardly to lie directly against the portion 12. From this construction the end 15 of each of such extremities lies directly under the locking element 11 to reinforce such element and to insure its positive engagement with the surface 3.

By forming the clamp to provide the outwardly extending portions 13 it will be seen 75 that such portions may be grasped by the hand of the operator to facilitate attachment of the cap 5 or removal of the same from the bottle. In removing the cap from the bottle the portions 13 are manipulated 80 so that they may be sprung away from each other sufficiently to disengage the elements 11 from the surfaces 3. The clamp can then be rotated so as to bow the portions 12 thereof into registration with the said diametrically opposite recesses 4. The cap 85 may then be withdrawn from the bottle by moving the same upwardly from the neck. The construction of the device described is extremely desirable in that, owing to the 90 provision of the surfaces 3 and the provision of the coöperating spring clamp, therefor, should the latter lose its resiliency after frequent adjustments on the bottle it may be engaged at new points on the surfaces 3. These surfaces effectively form 95 means to prevent rotation of the clamp after the same has been adjusted. It is desirable to place a packing such as the washer shown at 16, between the cap and the neck 100 of the bottle. This insures a perfect air tight connection when the clamp is in its applied position.

I claim:—

The combination with a bottle having a 105 neck provided with oppositely inclined corrugated surfaces, of a cap removably fitted to the neck, and a clamp comprising a substantially elongated member pivoted intermediate of its ends to the central portion of 110 the cap, said strip being bowed on opposite sides from its pivotal point and thence ex-

2
tended downwardly against the sides of the neck and having terminals extending longitudinally to the plane of the neck of the bottle and engaging therewith, each terminal being bent upon itself so that the rigidity of each terminal exceeds that of the intermediate portion of the elongated clamp member and each of said terminals being provided with an offset portion underlying

and yieldingly engaging the notch surface 10 of the flange of the neck.

In testimony whereof I affix my signature in presence of two witnesses.

ALBERT J. SLAUGHTER.
